Primary Examiner—A. Hugo Word*Assistant Examiner*—Doris Clark*Attorney, Agent, or Firm*—Quarles & Brady**[57] CLAIM**

The ornamental design for a folding room divider, as shown and described.

DESCRIPTION

FIG. 1 is a perspective view taken from the left side of a folding room divider, showing my new design; FIG. 2 is a side perspective view thereof shown with the panels in an extended position; FIG. 3 is a left side elevational view thereof; FIG. 4 is a right side elevation view thereof; FIG. 5 is a front elevation view thereof; FIG. 6 is a back elevation view thereof; and, FIG. 7 is a top plan view thereof. The broken lines showing mounting brackets, a floor, and a wall are for illustrative purposes only, and form no part of the claimed design.

FIG. 1

FIG. 2

FIG. 7

FIG. 3

FIG. 5

FIG. 4

FIG. 6
